(57) **CLAIM**

I claim the ornamental design for a wire support, as shown and described.

DESCRIPTION

FIG. 1 is a perspective view of the claimed design;
 FIG. 2 is a front view thereof;
 FIG. 3 is a left side view thereof;
 FIG. 4 is a rear view thereof;
 FIG. 5 is a right side view thereof
 FIG. 6 is a top view thereof;
 FIG. 7 is a bottom view thereof; and,
 FIG. 8 is another front view thereof.
 The broken lines in the drawings depict unclaimed environmental subject matter, are for illustrative purposes only, and form no part of the claimed design.
